CLAIM

The ornamental design for a positive lock hanger for a telephone handset, as shown and described.

DESCRIPTION

FIG. 1 is a perspective view of an exemplary positive lock hanger for a telephone handset according to the present invention;

FIGS. 2 and 4 are respective top and bottom plan views of the exemplary hanger hereof;

FIGS. 3 and 5 are respective side elevational views of the hanger hereof;

FIGS. 6 and 7 are respective end elevational views of the exemplary hanger hereof;

FIG. 8 is a perspective view of a further embodiment of the positive lock hanger for a telephone handset according to a second embodiment of the present invention;

FIGS. 9 and 11 are respective top and bottom plan views of the exemplary hanger illustrated in FIG. 8;

FIGS. 10 and 12 are respective side elevational views of the exemplary hanger illustrated in FIG. 8; and

FIGS. 13 and 14 are respective end elevational views of the exemplary hanger illustrated in FIG. 8.
